(No Model.)

J. SHACKLETON.
HEATING APPARATUS.

No. 373,693.

Patented Nov. 22, 1887.

Fig. 1.

UNITED STATES PATENT OFFICE.

JOSEPH SHACKLETON, OF NEW YORK, N. Y.

HEATING APPARATUS.

SPECIFICATION forming part of Letters Patent No. 373,693, dated November 22, 1887.

Application filed May 7, 1887. Serial No. 237,435. (No model.)

To all whom it may concern:

Be it known that I, JOSEPH SHACKLETON, a citizen of the United States, residing at New York, in the county and State of New York, 5 have invented new and useful Improvements in Heating Apparatus, of which the following is a specification.

My invention consists in an improved apparatus for heating railway-cars, both by steam and hot water, and has for its object to rapidly heat the car at the start by the use of steam alone, and subsequently to maintain a constant temperature throughout the car by the use of hot water.

15 The specific construction of the apparatus is more fully pointed out in the following specification and claims, and illustrated in the accompanying drawings, in which—

Figure 1 represents a sectional elevation of 20 a car equipped with my improvement. Fig. 2 is a section in the plane $x x$, Fig. 1, of a portion of the car. Fig. 3 is a vertical section, on a larger scale than the preceding figures, of a portion of the apparatus.

25 Similar letters indicate corresponding parts. In the drawings, the letter A, Figs. 1 and 2, designates a railway-car, provided at its rear and forward ends and in diagonally-opposite corners with compartments B, such as contain 30 a water-closet, C, and a basin, D, Fig. 1.

S is a main steam-supply pipe, which enters the car at its forward end and passes through the same, said pipe being bent on entering the car, Fig. 2, to clear the lamps and other appendages suspended from the roof of the same. This steam-supply pipe S can be connected with the locomotive-boiler or with a supplementary boiler located at the rear of the tender, to supply live steam. Suitable flexible 35 couplings, such as E, Figs. 1 and 2, are used to connect the steam-supply pipes S of adjacent cars. A radiator, R, Fig. 1, is located at each end of the car, and supplied with steam from the steam-pipe S by a branch pipe, F, 40 having a suitable valve, f.

W is a water-pipe, Figs. 1, 2, and 3, extending along the bottom of the car and to one side of the same. At one of its ends it is connected with the radiator R, to supply water to the 45 same, and its other end connects by means of a pipe, G, with a tank, T, located above the compartment B. A suitable valve, g, is intro-

duced in the pipe G. Two such water-pipes W and two tanks T are used for each car, the same being located, respectively, on opposite sides thereof, and in general all the parts, with the exception of the steam-supply pipe S, are in duplicate.

Each water-pipe W is provided with two upwardly-projecting branches or legs, H H, 60 which are closed at their tops by suitable plugs or caps, and centrally within each of the said water-pipes is placed a steam-pipe, S', (Fig. 3 especially,) the ends of which extend into the legs H H and rise to a certain level therein. 65 The steam-pipe S' is connected with the main steam-pipe S by a branch pipe, s, in which latter a suitable valve, V, is placed.

Water is supplied to the water-pipe W and to the radiator R from the tank T, and the water fills the same and can rise to a level in the water-legs, which is determined by an overflow-pipe, O, connected with one of the water-legs. This overflow should be on a level above the top of the radiator, so that the latter will 75 also be filled. The overflow-pipe projects into one of the water-closets C, or it can be led directly through the bottom of the car. By means of a cock, o, therein the escape of liquid can be prevented, when desired. The live 80 steam, entering the steam-pipe S' from the main supply-pipe S, heats the water contained in the pipe W and in the radiator R. The condensing steam causes a gradual rise of water in the water-pipe and the surplus water flows out 85 through the overflow-pipe O. The water thus heated, combined with the heat radiating from the supply-pipe S, warms the car.

To remove the water from the pipe W when the car is laid over for the night, I provide 90 means for drawing up said water into the tank T, as follows: A pipe, I, Figs. 1 and 2, is led from the main supply-pipe S into the tank, and the tank itself is provided with an air-cock, J, so that by blowing live steam through 95 the tank a vacuum is formed therein. By closing a valve, v, in the pipe I, and also the air-cock J, and subsequently uncoupling the cars, so as to permit air to enter the water-pipe W through the steam-pipe S, pipe I, and the radiator, the water is forced up into the tank, and by closing the valve g of the pipe G it is retained therein.

Before starting the car in the morning the

steam-pipe S is connected with the boiler of the locomotive or the supplementary boiler on the tender, and steam enters the large water-pipe W and also the radiator, which pipe W 5 then serves as a steam-pipe having a large area of radiating-surface, so that the car is heated very rapidly. After the car is heated the water in the tank is allowed to flow into the water-pipe S from the tank T.

10 In cases where it is desired to have the car continually heated while in the yard, I provide an additional steam-generator, K, which is located at the bottom of the car and can be heated with a gaseous fuel. The steam-supply pipe k of this steam-generator is connected with the steam-pipe S, and therefore with the entire heating apparatus. A suitable connection with a gas-reservoir is made by means of a flexible tube, k', Fig. 1.

15 It will be observed that by the use of my system a car can be rapidly heated before the start by the use of live steam and pipes having a large radiating-surface, and subsequently the car can be heated by hot water.

20 What I claim as new, and desire to secure by Letters Patent, is—

1. The combination, in a car-heater, of a steam-supply pipe extending longitudinally through the car, a water-pipe extending 30 through said car, a radiator to which one end of each of said pipes is connected, an auxiliary steam-pipe extending longitudinally within the water-pipe and having openings communicating with the latter, and a pipe connecting the main steam-pipe with the auxiliary steam-pipe, substantially as described.

2. The combination, in a heating apparatus, of a water-pipe having vertical water-legs, one of which is provided with an overflow-pipe,

a radiator, an elevated tank connected with 40 said water-pipe, a steam-pipe arranged within the water-pipe and extending vertically into and opening within the water-legs, a main steam-supply pipe, and a branch pipe connecting the main steam-supply pipe with the 45 auxiliary steam-pipe, substantially as described.

3. A car-heater consisting of a steam-supply pipe, a water-pipe, an auxiliary steam-pipe arranged within and communicating with 50 said water-pipe, a pipe connecting the steam-supply pipe with the auxiliary pipe, an overflow-pipe for the water-pipe, an elevated water-tank connected with the latter and provided with an air-cock, and a pipe connecting the 55 steam-supply pipe with the tank for creating a vacuum in the tank, substantially as described.

4. The combination, in a car-heater, of a steam-supply pipe, a water-pipe, an auxiliary 60 steam-pipe within and opening into the water-pipe, a branch pipe connecting the steam-supply pipe with the auxiliary steam-pipe, an overflow-pipe for the water-pipe, a radiator 65 connected with the steam-supply and water pipes, an elevated tank having an air-cock, and a pipe, I, connecting the steam-supply pipe with the tank and provided with an opening and closing cock, v, substantially as and for the purpose described.

In testimony whereof I have hereunto set my hand and seal in the presence of two subscribing witnesses.

JOSEPH SHACKLETON. [L. S.]
